Specification for Design.

Patented Mar. 9, 1920.

Application filed June 10, 1919. Serial No. 303,243. Term of patent 14 years.

To all whom it may concern:

Be it known that I, FRANK S. RODE, a citizen of the United States of America, residing at Jeannette, in the county of Westmoreland and State of Pennsylvania, have invented a new, original, and ornamental Design for a Lifting-Jack, of which the following is a specification, reference being had

to the accompanying drawing, forming part thereof.

The figure is a view in perspective of a lifting jack, showing my new design.

I claim:

The ornamental design for a lifting jack, as shown.

FRANK S. RODE.
